AIR LATERAL FOR ICE CANS

Filed April 16, 1930

UNITED STATES PATENT OFFICE

NORMAN M. SMALL, OF WAYNESBORO, PENNSYLVANIA, ASSIGNOR TO FEICK COMPANY,
OF WAYNESBORO, PENNSYLVANIA, A CORPORATION OF PENNSYLVANIA

AIR LATERAL FOR ICE CANS

Application filed April 16, 1930. Serial No. 444,817.

This invention relates to devices for supplying air to ice cans during the freezing of the water in them in order to agitate the water to permit it to freeze free of impurities.

Referring to the accompanying drawings, which are made a part hereof and on which similar reference characters indicate similar parts,

10 Figure 1 is a perspective view showing a plurality of my devices applied to an air lateral,

Figure 2, a section on an enlarged scale on line 2-2 of Figure 1,

15 Figure 3, a side elevation, and

Figure 4, a side elevation of the holding block.

In the drawings numeral 10 indicates an air supply pipe which may be connected to 20 a source of air under pressure, not shown. In order to hold it in position above the ice cans, this pipe may have one or more blocks 25 secured thereon by means of set screws 12. The block 11 is slotted at each side, as shown at 13, and tapered so that the lower end is not as wide as the upper end and fits in a notch in one of the partitions 15 between the ice cans. The block 11 prevents axial as well as turning movement of the pipe 10. The 30 pipe 10 lies in notches 14 in the partitions 15. A strap of iron 16 is bent over and secured to the pipe 10 by means of a bolt 17.

The lower end of the strap 16 is bent into U-shape, as shown at 18. The sides of the U are 35 slotted at 19 to receive the small ends 20 of an enlarged cylindrical swivel 21 formed as a part of the nozzle 22. The swivel 21 has a short pipe 23 entering it at one side and a relatively long end 22 at the other side, which 40 is threaded at 24. The lower end 25 of the pipe 22 is smaller than the main portion of this pipe to provide a shoulder at 26. A short rubber tube 27 is slipped upon the pipe 22 and held by the threads 24. A relatively long 45 metal tube 28 is slipped up around the metal tube 25 within the rubber tube 27. Preferably a small metal ring 29 is inserted within the end of the rubber tube 27. The tube 28 fits substantially air tight within the rubber 50 tube 27. A nipple 30 is screw threaded in a

side of the pipe 10 and extends a short distance without the pipe and has a short rubber tube 31 pressed thereon, the lower end of the tube 31 being secured to the short end 23 which extends out from the swivel 21. A 55 latch 32 is pivoted at 33 to the member 16 and has its lower end formed into a U-shaped catch which fits around the U-shaped portion 18 on the lower end of the member 16. The ends 34 of the catch 32 fit just above the trunnions 20 on the swivel 21 to hold this in position but to permit the pipe 28 together with its parts to swing on the trunnions 20. Obviously any number of suspended pipes 28 together with the parts cooperating with it 60 may be attached to any one air lateral 10.

While the pipes 28 have been shown as suspended to swing laterally of the ice cans obviously they could be suspended to swing the long way of the cans by having the trunnions 70 mounted parallel with the pipe 10 instead of at right angles to the pipe 10, as shown.

From the foregoing description it will be apparent that the air lateral 10 together with all of its connections may be lifted out of the cans. This is ordinarily done just before the ice cakes in the cans freeze shut. By means of the block 11 the tube 10 is positioned so that the pipes 28 will swing centrally of the ice can.

In case any of the tubes 28 become frozen in the ice cake they may be slipped out of the rubber tubes 27 and later removed from the ice cake. By pushing back the latch 32 the swivel 21 may be lifted out of its supporting 80 bracket and the parts separated so as to be cleaned if necessary.

The whole assembly is simple, easily put into position and taken out, easily taken apart to clean if necessary and efficient, operating 90 to deliver air into the center of the forming ice cake.

It will be obvious to those skilled in the art that various changes may be made in my device without departing from the spirit of the invention and therefore I do not limit myself to what is shown in the drawings and described in the specification, but only as indicated in the appended claims.

Having thus fully described my said in- 100

vention, what I claim as new and desire to secure by Letters Patent, is:

1. Means for supplying air to ice cans comprising a main air supply pipe removably positioned upon partitions between the cans, means for securing the said pipe against axial and turning movement, and a plurality of air supplying pipes suspended from and at intervals along said pipe, said supplying pipes being permitted to swing in one plane only, substantially as set forth.
2. Means for supplying air to freezing ice cans comprising a main air supply pipe positioned on partitions between the said cans, a block secured upon the pipe engageable with a notch in one of the partitions to hold the pipe against axial and turning movement, a plurality of air supplying conduits suspended from said main supply pipe, means for permitting these said conduits to swing in one direction laterally of the cans but to be held against swinging in any other direction, substantially as set forth.
3. Means for supplying air to freezing ice cans comprising a main air supply pipe positioned on partitions between the said cans, a block secured upon the pipe engageable with a notch in one of the partitions to hold the pipe against axial and turning movement, a plurality of air supplying conduits suspended from said main supply pipe, means for permitting these said conduits to swing in one direction laterally of the cans but to be held against swinging in any other direction, the said conduits being removably attached to the said main supply pipe, substantially as set forth.
4. Means for supplying air to freezing ice cans comprising a main supply pipe, means for holding it against axial and turning movement above the ice cans, brackets secured on said pipe, a plurality of pipes suspended from said brackets, said pipes being flexibly connected to the said main pipe, substantially as set forth.
5. Means for supplying air to freezing ice cans comprising a main supply pipe, means for holding it against axial and turning movement above the ice cans, a plurality of brackets secured in spaced relation on said pipe, a plurality of pipes suspended from said brackets, said pipes being flexibly connected to the said main pipe, and means on the said suspended pipes for limiting their swinging to one direction only, substantially as set forth.
6. Means for supplying air to freezing ice cans comprising a main supply pipe, a plurality of brackets secured in spaced relation on said pipe, a swivel joint carried by said bracket, said joint having a flexible conduit connecting it to the main pipe and having a pipe suspended from its lower side, the said swivel joint permitting said last-named pipe

to swing in one direction only, substantially as set forth.

7. Means for supplying air to freezing ice cans comprising a main supply pipe, a plurality of depending supply pipes positioned to hang in the center of each ice can, said depending supply pipes comprising a swivel joint, means for mounting it to swing in one direction in the said ice cans, a flexible connection between the swivel joint and the main supply pipe, a rubber sleeve positioned on the said swivel joint, and a metal tube positioned within the said rubber sleeve and frictionally held therein, substantially as set forth.

8. Means for supplying air to ice cans through a tube with a slip joint comprising a tube, a rubber hose stripped over one end of the tube, a ring holding open the mouth of the hose, another tube adapted to enter the ring and being pushed over the first tube and within the rubber hose to make a substantially air tight connection between tubes and a substantially rigid connection as to bending at the joint, substantially as set forth.

9. Means for supplying air to ice cans through a tube with a slip joint comprising a tube with the one end of reduced outside diameter forming a shoulder, a rubber hose stripped over the reduced end and shoulder of the tube, a ring holding open the mouth of the hose, another tube adapted to enter the ring and be pushed over the first tube against the shoulder and within the rubber hose to make a substantially air tight connection between tubes and a substantially rigid connection as to bending at the joint, the shoulder to act as a stop to regulate the distance of entering tubes, substantially as set forth.

In witness whereof, I have hereunto set my hand at Waynesboro, Pennsylvania, this 14th day of April, A. D. nineteen hundred and thirty.

NORMAN M. SMALL.
